(57) **CLAIM**

The ornamental design for a firearm hand guard, substantially as shown and described.

DESCRIPTION

FIG. 1 forward lower left perspective view of a firearm hand guard according to the present invention;

FIG. 2 is a right side elevation view of the firearm hand guard shown in FIG. 1;

FIG. 3 is a left side elevation view of the firearm hand guard shown in FIG. 1;

FIG. 4 is a bottom plan view of the firearm hand guard shown in FIG. 1;

FIG. 5 is a top plan view of the firearm hand guard shown in FIG. 1;

FIG. 6 is a rear elevation view of the firearm hand guard shown in FIG. 1; and,

FIG. 7 is a front elevation view of the firearm hand guard shown in FIG. 1.

The broken lines are for illustrative purposes and represent environmental structure and unclaimed portions of the invention and therefor form no part of the claimed design. The dash-dot lines are for illustrating boundaries of the claimed portions of the invention and form no part of the claimed design.

1 Claim, 6 Drawing Sheets
